BOX FOR CIGARETTES OR THE LIKE

Felix Collado Otero and Juan Bautista Pascual Esteve,
both of Calle Cienfuegos 75-77, Havana, Cuba

Filed Dec. 19, 1958, Ser. No. 53,825

Term of patent 14 years

(Cl. D58—12.6)

We claim:
The ornamental design for a box for cigarettes or the like, as shown and described.
